UNITED STATES PATENT OFFICE.

EMIL F. BUSINGER, OF NEW YORK, N. Y.

STOP MECHANISM FOR LOOMS.

1,363,492.

Specification of Letters Patent. Patented Dec. 28, 1920.

Application filed May 8, 1920. Serial No. 379,710.

To all whom it may concern:

Be it known that I, EMIL F. BUSINGER, a citizen of the United States, residing at the borough of the Bronx, city of New York, 5 county of Bronx, and State of New York, have invented a new and useful Improvement in Stop Mechanism for Looms, of which the following is a specification.

This invention relates to stop mechanisms 10 for looms, particularly looms using drop-box or shuttle-lifting mechanism for weaving in colors, and which employ a jacquard mechanism, dobby heads or cams to control the pattern.

15 It is well known that severe damage and loss of time and material are apt to result from continued running of the loom when its mechanism fails to function properly, and this is particularly the case with respect 20 to Jacquard looms which employ drop-box or shuttle-lifting mechanism for weaving vari-colored patterns. Continued running of these looms when the pattern controlling mechanism fails to synchronize with the 25 drop-box or shuttle-raising mechanism is apt to result in breaking the shuttles, smashing out the threads, tangling the threads in the machinery, breaking the shuttle rack and pinions or cause the wrong color weft 30 to be woven.

Likewise the above-mentioned harm is likely to follow in consequence of the breaking of the shuttle-lifting chains, or, when, 35 for any reason, the shuttles stay improperly in raised position, or when the regulator needle of the jacquard fails to enter the hole in the jacquard card provided therefor.

To avoid the above damage when the 40 parts of the loom fail to function properly, it is necessary to stop the loom without delay, and for this purpose an operator is usually relied upon to watch the loom carefully and stop the loom manually whenever anything goes wrong.

45 One of the objects of this invention is to provide a stop mechanism for looms, whereby the loom will be automatically and promptly stopped whenever the pattern-controlling mechanism fails to synchronize 50 with the drop-box or shuttle-lifting mechanism.

Another object of this invention is to provide means adapted to automatically and promptly stop the loom whenever the shuttle-beam lifting chains break, or whenever 55 the shuttle-beam stays improperly in raised

position, or whenever the regulator needle of the jacquard fails to enter its hole in the jacquard card.

A further object is to provide simple and 60 efficient means for automatically stopping a loom whenever the ground weft or proper color weft is not woven at the proper time.

A further object of the invention is to provide a simple, inexpensive and efficient 65 automatic stop mechanism for looms, and one which may be readily mounted on a loom without interfering with or requiring severe structural alterations of the loom parts, and one which is sure and positive in 70 operation, and at the same time does not interfere with the usual manually actuated means for starting and stopping the loom.

Other objects will be in part obvious and 75 in part pointed out hereinafter.

While the invention may be applied to looms employed for weaving either wide or narrow fabrics and in which the pattern is controlled by cam levers, dobby heads or jacquards, the present embodiment has been 80 illustrated in connection with a typical narrow-ware loom such as that shown in the patent to O. W. Schaum, No. 786,237 of March 28, 1905, to which reference may be had for a more complete showing of certain 85 well known elements of the loom mechanism which form no part of this invention.

In the accompanying drawings,

Figure 1 is a side view of a loom with the 90 stop mechanism mounted thereon and showing above in diagrammatic perspective the method of connecting the stop mechanism with a jacquard mechanism forming part of the loom;

Fig. 2 is a front view of a portion of the loom;

Fig. 3 is a section of part of the stop mechanism on the line 3—3 of Fig. 1;

Fig. 4 is a sectional view on the line 4—4 100 of Fig. 1;

Fig. 5 is a perspective view of one possible method of connecting the stop mechanism with a belt-shifting arm of the loom; and

Fig. 6 is a sectional view of Fig. 4 on the line 6—6.

Similar reference characters refer to similar parts throughout the several views of the drawings, in which—

1 represents a narrow-ware Jacquard loom of usual construction adapted to weave vari-

colored figured cloth by the insertion in predetermined sequence of wefts of different colors, and comprises the usual frame 2, fixed driving pulley 3, loose pulley 4 and 5 belt-shifting arm 5 adapted to be moved and thereby shift driving belt 6 from one pulley to the other to effect the starting or stopping of the loom. Rock arms 7 carry the usual lay beam 32, which as usual is rocked in response to the rotation of the main shaft, gear wheel 40 and the consequent to-and-fro movement of the link 41 connected thereto. Two transverse shuttle-beams 8 are spaced apart, as by vertical bars 36, and carry the usual shuttle blocks and shuttles of which two banks are shown. The beams 8 are movably secured to rigid upward extensions 33 on the lay beam so as to rock to-and-fro therewith but to be capable of vertical movement relative to the latter sufficient to bring one or other of the several banks of shuttles into the plane of the sheds formed as usual in the weft threads between the shuttle-carrying blocks. Any suitable means, such as bell crank levers 35 (of which one is shown) are provided for moving the shuttle-beams and shuttles into predetermined positions in response to movement of the usual color regulating needles of a jacquard mechanism 30 to cause the ground weft or the proper color weft to be woven in predetermined sequence.

The drawings show a jacquard mechanism which may be of usual type and is adapted to govern a two shuttle weft, having a regulator needle 9 adapted to enter regulator hole 10 whenever it appears in a card of the jacquard card train. As usual, this needle is adapted to co-operate with a jacquard hook 11 adapted to be raised by a knife 12 whenever the needle 9 enters a regulator hole, and governs the pick mechanism to cause a pick to be taken whenever the needle 9 fails to enter a hole 10 in card and not otherwise. This hole 10 appears only in the figure or color cards, as is usual.

The stop mechanism comprises a member or bar 13 pivotally connected at one end, as at 14, to one arm 15 of a bell crank lever pivotally mounted on the loom frame 2, as at 16, the other arm 17 of said lever engaging belt-shifter 5 through a pivotally connected member 18, so that horizontal movement of member 13 toward the left (Fig. 1) will cause the belt 6 to be shifted onto the loose pulley 4 and effect the stopping of the loom. Member 13 is supported near its outer end, as at 19, by an attached cord or wire 20 leading over a pulley 21 mounted on a bracket 34 carried by lay 32, the wire 20 being fastened to beam 8, as at 22, so that whenever the beam is raised, member 13 will fall, and, whenever the beam is lowered, member 13 will rise. A pusher member or bar 23 is pivotally mounted near one end on rock arm 7, as at 24, and is supported at its

other end by a second cord or wire 25 attached to jacquard hook 11, so that member 23 will be raised whenever regulator needle 9 enters a hole in the jacquard card, and will be lowered from that position when 70 needle 9 does not enter a hole in the card.

From the above it is evident that, whenever regulator needle 9 enters a hole in the jacquard card, shuttle-beam 8 lowers, thereby raising member 13, and simultaneously 75 member 23 will also be raised by means of wire 25. Also, member 23 will partake of oscillating movement with rock arms 7, while member 13 will normally remain horizontally stationary. The stop mechanism is 80 so arranged that whenever the above described simultaneous vertical movement of members 13 and 23 fails, the movement of bar 23 toward the left in Fig. 1 will cause member 13 to be moved to the left, and thus 85 automatically effect a stopping of the loom.

Means for accomplishing this result comprise a depending lug 26 fastened to member 13, as at 27, and a lug or projection 28, formed or mounted on member 23, adapted 90 to move in and out of a recess 29 formed in member 26, when the loom is running in normal condition and so long as members 13 and 23 move vertically in synchronism. The outer end of bar 13 rides between the 95 two vertical prongs of a guide fork 37 mounted on bar 23, which fork maintains the proper lateral relationship between bars 13 and 23 during their travel. When members 13 and 23 do not move vertically in 100 synchronism, lug 28 is adapted to engage a surface 30 or a surface 31 formed on lug 26, in which event movement of bar 23 to the left will effect the stopping of the loom as above described. When the jacquard mechanism does not synchronize with the shuttle lifting and lowering mechanism, projection 105 28 is adapted to strike one of these surfaces 30 or 31 and effect the stopping of the loom. Whenever the jacquard needle 9 fails to 110 enter a hole at the proper time but the beam 8 lowers, projection 28 will engage surface 31 and cause the loom to stop; and, again, whenever the regulator needle 9 enters a hole in a card but for any reason beam 8 115 does not lower, projection 28 will engage surface 30 of lug 26 and cause the loom to stop. Also, when the shuttle-lifting chains break and the shuttle-beam stays lowered, while the jacquard mechanism operates for 120 raised shuttles, projection 28 will engage surface 31 of lug 26 to stop the loom.

It is apparent from the above that this device may be installed upon any one of a number of varieties of looms and irrespective of the number of colors or shuttles with which the loom is designed to operate. When more than two banks of shuttles are used, the recess 29 in lug 26 should be made sufficiently wide to allow for the proper po- 130

sitioning of the shuttles without actuating the stop mechanism. It is understood that the parts should be adjusted according to the particular extent of drop of the shuttle-beam, the rise of the jacquard hook being practically the same in all looms.

It is understood that many changes and embodiments of this invention may be made without departing from the spirit and scope 10 thereof.

I claim:

1. In a loom, the combination with means for starting and stopping the operation thereof, a pattern controlling mechanism, a 15 plurality of shuttles, a mechanism for raising and lowering said shuttles, said mechanisms coöperating to produce a given design, a lay, and means for rocking said lay; of two movable members, means for moving 20 one of said members in one direction in response to the operation of said pattern controlling mechanism, means for moving the other of said members in one direction in response to the raising and lowering of said 25 shuttles, and means responsive to the rocking of said lay for moving one of said members in a different direction into engagement with the other of said members to move said last mentioned member in a different direction 30 to operate said loom stopping means whenever the coöperative relationship between said mechanisms is destroyed.

2. In a loom, in combination, shuttle carrying means, means to rock said shuttle carrying means, means to raise and lower said shuttle carrying means, a jacquard mechanism adapted to synchronize with said second mentioned means, a movable member, means adapted to impart predetermined 40 movement to said member in response to rocking movement of said shuttle carrying means, means to impart a different predetermined movement to said member in response to movement of said jacquard mechanism, a 45 second movable member, means to impart predetermined movement to said second member in response to the raising and lowering of said shuttle carrying means, and means adapted upon predetermined relative 50 movement of said movable members to stop the loom.

3. In a loom, in combination, a shuttle-beam, means adapted to raise and lower said shuttle-beam, a jacquard mechanism 55 adapted to operate in synchronism with said shuttle-beam operating means, means for

stopping the loom upon failure of said means to synchronize with said mechanism, comprising a pair of independently movable members adapted to move in synchronism 60 while said means and mechanism operate in synchronism, said synchronism being adapted to be destroyed upon failure of synchronism of said means and mechanism, whereby relative movement of said members 65 effects the stopping of said loom.

4. In a loom, in combination, a shuttle-beam, means adapted to raise and lower said shuttle-beam at predetermined times, a jacquard mechanism adapted to govern the 70 raising and lowering of said shuttle-beam, a stop mechanism comprising a member movable in a predetermined manner in response to said jacquard mechanism and movable in another predetermined manner in response 75 to rocking movement of said shuttle-beam, and a second member movable in a predetermined manner in response to the raising and lowering of said shuttle-beam and adapted to be engaged and moved by said first movable 80 member upon the failure of said jacquard mechanism to properly govern the means for raising and lowering the shuttle-beam, and means whereby the last mentioned movement of said second member effects the stop- 85 ping of said loom.

5. A stop mechanism for looms, comprising, in combination, a movable member adapted to be mounted on and be movable with the rock arm of a loom and adapted to 90 be connected with a jacquard mechanism to partake of predetermined movement with the movement of a jacquard hook, a second movable member adapted to be mounted on said loom and to be movable in a predetermined manner in response to the raising and lowering of the shuttle-beam and to be connected with the belt shifting arm of said loom whereby its movement in a predetermined direction effects the stopping of said 100 loom, said two movable members being adapted to coöperate to permit the continued running of the loom when the jacquard mechanism properly synchronizes with the shuttle raising mechanism, but to effect a 105 stopping of the loom whenever said jacquard mechanism fails to synchronize with the raising and lowering of the shuttles.

Signed at New York city, N. Y., this 7th day of May, 1920.

EMIL F. BUSINGER.
